UNITED STATES PATENT OFFICE

97,449

DESIGN FOR A REAR MEMBER FOR A VELOCIPED FRAME

Bert J. Anderson, Hammond, Ind.

Application May 22, 1935, Serial No. 56,955

Term of patent 14 years

To all whom it may concern:

Be it known that I, Bert J. Anderson, a citizen of the United States, residing at Hammond, in the county of Lake and State of Indiana, have invented a new, original, and ornamental Design for a Rear Member for a Velocipede Frame, of which the following is a specification, reference being had to the accompanying drawing, forming part thereof.

Figure 1 is a perspective view of the rear member for a velocipede frame of this invention.

Figure 2 is a top plan view thereof.

Figure 3 is a front elevation of the member.

I claim:

The ornamental design for a rear member for a velocipede frame as shown.

BERT J. ANDERSON.
